UNITED STATES PATENT OFFICE.

JOEL C. WELLS, OF SOUTHBIDGE, MASSACHUSETTS.

DESIGN FOR A HANDLE FOR EYEGLASSES AND LORGNETTES.

44,504.

Specification for Design.

Patented Aug. 12, 1913.

Application filed May 15, 1912. Serial No. 697,557. Term of patent 14 years.

To all whom it may concern:

Be it known that I, JOEL C. WELLS, a citizen of the United States, residing at Southbridge, in the county of Worcester and State of Massachusetts, have invented a new and original ornamental Design for a Handle for Eyeglasses and Lorgnettes, of which the following is a specification, reference being made to the accompanying drawings, forming a part hereof.

My invention relates to an improved design for a handle for use upon eyeglasses, lorgnettes or similar structures and the object of my invention is the provision of a

novel and improved form of ornamental and attractive design of handle for this purpose.

The figure represents a view slightly in perspective of my improved handle.

I claim:

The ornamental design for a handle for eyeglasses and lorgnettes as shown.

In testimony whereof, I affix my signature in the presence of two witnesses.

JOEL C. WELLS.
